signor of one-half to Claramae Blum Burns,
New York, N. Y.

Application December 17, 1936, Serial No. 116,313

4 Claims. (Cl. 2—42)

This invention relates to a halter for women, to be worn with slacks, shorts, bathing suits and the like.

An object of the invention is to provide a halter of simple form and pleasing appearance.

Another object is to provide a halter which may be worn a plurality of ways to produce different effects.

Another object is to provide a halter of the above type which is cheap and simple to manufacture.

Various other objects and advantages will be apparent as the nature of the invention is more fully disclosed.

15 Although the novel features which are believed to be characteristic of this invention are pointed out more particularly in the claims appended hereto, the invention will be better understood by referring to the following description, taken in connection with the accompanying drawings in which certain embodiments thereof have been set forth for purpose of illustration.

In the drawings,

Figure 1 is a plan view of one form of a halter embodying the present invention;

Figures 2 and 3 are front and rear views respectively, illustrating one method of wearing the halter;

Figures 4 and 5 are front and rear views respectively, illustrating another method of wearing the halter; and

Figure 6 is a plan view of a modified form of halter.

Referring to the drawings more in detail, the 35 halter is shown in Figure 1 as comprising a pair of rectangular pieces of material 10 and 11, having corners 12 to 15 and 16 to 19 respectively. The corner 13 of the piece 10 and the corner 19 of the piece 11 are joined by a narrow strap 20. 40 The strap 20 is attached to the pieces 10 and 11 by suitable means, such as stitches (not shown), and forms a continuation of the diagonals of said pieces.

In the form illustrated, the pieces 10 and 11 are 45 made of silk cut to appropriate size, and the cut edges being hemmed to prevent unraveling. It is apparent that instead of silk fabrics, other fabrics, either knitted or woven, and formed of cotton, wool rayon, synthetic fibers of all kinds, or 50 mixtures thereof, may be used. Also rubber sheet materials, rubberized fabrics, coated fabrics, etc. may be used. To enhance the attractiveness of the halter, the pieces 10 and 11 may be decorated in any desired manner.

55 The strap 20 may be formed of the same mate-

rial as the pieces 10 and 11 or may be formed of a different material. Also, the strap may be decorated to harmonize or contrast with the pieces 10 and 11.

The halter illustrated in Figure 1 may be worn in several ways. As shown in Figures 2 and 3, it may be worn by positioning the strap 20 around the back of the neck, passing the corners 12 and 16 under the arms and tying them together at the back, tying corners 14 and 18 together at the front, and bringing corners 15 and 17 together and joining the same by a pin 21 to the front of the waistband 22 of the shorts, slacks, bathing suit or the like 23.

When the halter is worn in the manner described in the preceding paragraph, it gives the effect of a full front and an open back. It is to be noted, however, that the corners 15 and 17 may be separated somewhat and joined to the waistband in spaced relationship, in which case a brassière effect is obtained.

Another way of wearing the halter is illustrated in Figures 4 and 5. In this embodiment, the strap 20 is positioned at the middle of the back; corners 12 and 16 are passed forwardly under the arms 25 and up to the back of the neck where they are tied together; corners 14 and 18 are tied together in front near the waistline; and corners 15 and 17 are allowed to fold back to form revers. If desired, the corners 15 and 17 can be tucked in or 30 they may be tied together to form a substantially closed front.

It will be evident that the halter may also be worn in various other ways to produce different effects. In the embodiment shown, the pieces 10 35 and 11 are approximately square. It will be obvious, however, that these pieces may be of other rectangular form or may be diamond-shaped, depending upon the effect desired. The strap 20 may be joined at other points on the periphery of 40 the pieces 10 and 11 or may extend at an angle to the diagonals. A plurality of different effects can thus be obtained, depending upon the position of the strap, the shape of the pieces and the manner in which it is worn.

45 In some instances, the pieces may be triangular in form. This embodiment is illustrated in Figure 6, in which pieces 25 are shown in the form of right-angled triangles, each having a hypotenuse 27 and a corner 29 positioned opposite thereto and joined by a strap 31. This form 50 may be worn in a manner similar to that illustrated in Figures 4 and 5 and will produce the effect shown therein with the exception of the revers. It will also be evident that the strap 55

31 may be joined to the other corners of the pieces 25 or at the other points on the periphery thereof with a corresponding change in effect when the halter is worn.

5 The component parts of the halter may be of such respective dimensions and sizes as to permit the halter to be worn as desired in any of the manners hereinbefore described by any woman irrespective of her size. Also, the straps 20 10 and 31 may be of the adjustable type and/or may be of an elastic material, or a rope or chain.

15 Although certain particular embodiments of the invention have been shown and described for purposes of illustration, various changes and modifications may be made therein as will be apparent to a person skilled in the art. The invention is only to be limited in accordance with the following claims when interpreted in view of the prior art.

20 I claim:

1. A halter for women comprising a pair of triangular pieces of material and a strap joining said pieces and having one of its ends attached to one corner of one of said pieces and its other end attached to one corner of the said other piece, said strap being adapted to be positioned around the neck or back of the wearer, the second corners of each of said pieces being adapted to be passed beneath the arms and secured together by tying in a knot at the back of the wearer, and the third corners of each of said pieces being adapted to be secured together by tying in a knot at the front of the wearer.

2. A halter for women comprising a pair of pieces of material each having at least three corners, a strap joining said pieces and having one of its ends attached to one corner of one of said pieces and its other end attached to one corner of the said other piece, said strap being adapted to be positioned around the neck or back of

the wearer, the second corners of each of said pieces being adapted to be passed beneath the arms and secured together by tying in a knot at the back of the wearer, and the third corners of each of said pieces being adapted to be secured together by tying in a knot at the front of the wearer.

3. A halter for women comprising a pair of pieces of material, each having at least four corners, a strap joining said pieces and having one of its ends attached to one corner of one of said pieces and its other end attached to one corner of the said other piece, said strap being adapted to be positioned around the back to the neck of the wearer, the second corner of each of said pieces being adapted to be passed beneath the arms and secured together by tying in a knot at the back of the wearer, the third corners of each of said pieces being adapted to be secured together by tying in a knot at the front of the wearer, and the fourth corners of each of said pieces being adapted to be secured to the waistband of the wearer at the front.

4. A halter for women comprising a pair of pieces of material, each having at least four corners, a strap joining said pieces and having one of its ends attached to one corner of one of said pieces and its other end attached to one corner of the said other piece, said strap being adapted to be positioned across the back of the wearer, the second corners of each of said pieces being adapted to be passed forwardly beneath the arms and secured together by tying in a knot at the back of the wearer, the third corners of each of said pieces being adapted to be secured together by tying in a knot at the front of the wearer, and the fourth corners of each of said pieces being adapted to be folded outwardly to form revers.

LUCIE VON LEDERMANN. 40
